UNITED STATES PATENT OFFICE.

WILLIAM A. HARVEY, OF SCRANTON, PENNSYLVANIA.

PORTABLE REGULATABLE LAMP.

Application filed July 2, 1923. Serial No. 649,148.

My invention relates to electric light fixtures, and particularly to light fixture constructions embodying means for anchoring and preventing independent rotation between a socket rotatable for regulation and the housing designed to enclose the same.

There is at the present time, in extensive commercial use, sockets provided with a resistance unit regulatable by the rotation of 10 a shell for controlling the brilliance of the electric light adapted to be screwed into the socket. These sockets are constructed in accordance with the structure shown in U. S. Patent No. 904,826, granted November 24, 15 1908.

These sockets regulatable by rotation, as now commercially employed, are provided, as mentioned hereinbefore, with a shell portion, to which there is usually attached a 20 chain, the ends of which are passed through diametrically arranged guiding eyelets whereby the rotatable shell may be adjusted by pulling either end of the chain.

It has been found desirable to associate 25 this type of socket with lamp structures; and to this end my invention consists in the construction of the lamp which includes a housing for enclosing these sockets. Inasmuch as these regulating sockets are customarily 30 associated with the ordinary commercial type of standard socket, the regulating socket would in ordinary lamp structures be projected upwardly beyond the housing of the lamp, thus rendering the appearance 35 thereof unsightly. In my improved arrangement a housing is provided which effectively conceals the regulating socket.

It has also been found that the constant rotation of the shell of the regulating socket 40 causes the regulating socket to be unscrewed from the standard socket with which it is associated, and my invention has therefore as an object to provide means for effectively anchoring the regulating socket within the 45 housing of a lamp so that after the assembling of the lamp structure an unintentional disarrangement of the parts is prevented.

The various details of construction of my improved invention will be made more apparent as this description proceeds, especially when considered in connection with the 50 accompanying drawings, wherein;

Figure 1 is a longitudinal sectional view through a lamp structure, with certain parts in elevation, showing one form of my improved anchoring means;

Fig. 2 is a top plan view, partly in section, of the structure illustrated in Fig. 1, with the electric light bulb removed;

Fig. 3 is a bottom plan view of the structure illustrated in Fig. 1;

Fig. 4 is a fragmentary sectional view, partly in elevation, showing a modified form of anchoring means;

Fig. 5 is a detail perspective view of the 65 form of anchoring means illustrated in Fig. 4;

Fig. 6 is a view similar to Fig. 4, of another modified form of construction;

Fig. 7 is a detail perspective view of the 70 form of anchoring means illustrated in Fig. 6;

Fig. 8 is a fragmentary sectional view of a portion of the lamp structure, certain parts being shown in elevation, illustrating another form of anchoring means;

Fig. 9 is a top plan view of the structure illustrated in Fig. 8, the electric light bulb being removed; and,

Fig. 10 is a vertical sectional view, 80 through another type of lighting fixture, showing another form of anchoring means.

Referring now particularly to Figs. 1 to 3, the general arrangement of the structure and the first form of anchoring means will 85 be described. In the drawings the reference character 10 indicates the housing of a portable electric lamp, having an upwardly projecting extension 11 and a hollow base 12. A tubular member 13 extends upwardly 90 through the housing, and is threaded into the standard socket 14, which bears against a restricted neck portion 15 of the housing, while the lower end of the tubular member 13 passes preferably through a plate 16, arranged within the hollow base 12, and has threaded onto its end a nut 17, whereby the parts may be assembled and tied together. The wires to the socket 14, preferably enter 95 the base of the lamp structure and pass upwardly through the tubular member 13.

The reference character 18 indicates generally the regulating socket hereinbefore referred to, this socket being formed with an eyelet 19, to which a chain (not shown) is 105 attached, the ends of this chain passing through guiding eyelets 20, formed on the ends of arms 21, projecting rigidly from the socket 18 at diametrically opposed points. The eyelet 19 is secured to a shell portion of 110 the socket, which is rotatable relatively to the remainder of the socket, the rotation of

this shell operating to cut in and out the resistance for varying the degree of brilliancy of the light in the bulb 22.

The extension 11, formed on the housing 10, is admirably effective for concealing the socket 18, and it should be furthermore noted that I preferably employ, as an operating means for the regulating socket, a handle 23, secured to the rotatable shell of the 5 socket by clamping means 24, this handle and clamping means being constructed in accordance with my application, Serial No. 648,097, filed June 27, 1923. The shell of the socket 18 rotates relatively to the remainder 15 of the structure, the rotation being limited by the engagement of the eye 19 with either of the guiding eyes 20. It will be apparent that in adapting the socket for use in connection with lamp structures of 20 this character, I remove the customary operating chain and substitute therefor the operating handle 23.

In this form of my invention, independent rotation between the socket 18 and the 25 socket 14, or the rest of the lamp structure, is prevented by the provision of lugs 25, preferably cast integrally with the housing on the inside thereof, these lugs being arranged diametrically opposite one another 30 and being shaped to provide a pair of spaced lips or tongues 26, forming a recess 27, sufficient in width to receive the arms 21 of the guiding eyelets 20, as clearly illustrated.

In assembling the device, the socket 18 is 35 screwed into the standard socket 14, which has previously been attached to the tubular member 13. The member 13, with the attached sockets, is then passed downwardly into the casing, and the plate 16 inserted 40 over the end thereof, whereupon the nut 17 may be threaded onto the end of the tubular member 13. The tubular member 13 and sockets are so inserted that the arms 21 of the regulating socket 18 pass into operative 45 engagement with the lugs 25, these arms being straddled by the lips 26 and reposing in the recesses 27. Obviously, after the structure is tied together by means of the nut 17, independent rotation of the socket 50 with reference to the remainder of the structure, is prevented.

Referring now to Figs. 4 and 5, another form of my invention will be described. In these figures it will be noted that a clamping 55 ring 28, formed preferably of two complementary sections is provided, these ring sections being formed with angular ears 29, arranged in spaced parallel relation, and perforated to receive a clamping bolt 30, whereby the ring may be securely clamped around the standard socket 14.

Projecting upwardly from each of the ring sections is an arm 31, the upper end of which is bifurcated as at 32, forming a 60 pair of spaced ears 33, adapted to engage

both sides of the arms 21 of the guiding eyelets 20. Obviously, therefore, when the parts are assembled in the manner indicated in Fig. 4, independent rotation of the regulating socket 18 with reference to the standard socket 14 is prevented, and inasmuch as the socket 14 is securely mounted within the housing 10, a positive and rigid association of the complete structure is effected.

Referring now to Figs. 6 and 7, another 75 form of anchoring means will be described. In this instance a substantially U-shaped member 34 is provided, which is apertured as at 35 to receive the tubular member 13 of the lamp structure. An annular boss 36 is preferably formed around the aperture 35, which is adapted to rest upon the restricted portion 80 of the lamp housing.

As the lamp structure is tied together in the manner previously described, the member 34 will be rigidly positioned within the housing 10 and the upstanding arms thereof, which are bifurcated as indicated at 37, will come to engage the arms 21 of the regulating socket 18, so as to prevent the rotation 90 of this socket member, as will be immediately apparent.

Referring now more particularly to Figs. 8 and 9, still another form of my invention 95 will be described. For anchoring the regulating socket 18 in this instance there is provided a plurality, preferably two, bolts 38, threaded through the extension 11 of the lamp housing. The ends of these bolts are adapted to extend through the eyelets 20 of the regulating socket, as clearly illustrated. Lock nuts 39, threaded onto the bolts 38, are adapted to be forced against the eyelets 20 to securely lock the bolts in place and to effectively anchor the parts.

Obviously, after the structure has been assembled and the regulating socket screwed home as far as it will go, the necessary apertures may then be formed in the housing, and the bolts 38 threaded therein. Before the 110 bolts are permitted to pass into the eyelets 20, the locking nuts 39 are threaded thereon, the bolts 38 being thereafter inserted through the eyelets 20 as illustrated, whereupon the locking nuts may be tightened. It will be apparent that in this arrangement simple and effective means are provided for anchoring the regulating socket within the housing.

In Fig. 10, a form of portable electric lamp 115 simulating a candle and candle holder is illustrated. In this form, the housing 40, which simulates the candle, is of a diameter such as to frictionally engage the eyelets 20 with sufficient pressure to prevent a rotation of the socket 18. Thus, when the lamp structure is assembled, the sockets 19 with the eyelets 20 may be forced downwardly into the interior of the housing 40, whereupon the eyelets 20 will be sprung inwardly to a 120 small extent, the frictional contact between 125

these parts thereafter preventing an independent rotation of the regulating socket with reference to the remainder of the structure.

5 From the foregoing it will be apparent to those skilled in this particular art that my invention contemplates generally the provision of means for effectively and efficiently anchoring a socket regulatable by rotation 10 to the remainder of the lamp structure, either by directly connecting the guiding eyelets or arms therefor to the housing, or by anchoring these eyelet arms with means connected to another portion of the lamp structure. The several modifications herein described are indicative of its susceptibility to rearrangement and modification.

It should, therefore, be understood that my invention consists broadly in the association 20 with a portable lamp structure of anchoring means associated and interposed between the regulating socket and the remainder of the lamp structure for anchoring the regulating socket.

25 Having thus described my invention what I claim is:

1. In an electric lamp, the combination of

a housing; a standard socket rigidly mounted in said housing; a regulatable socket having a member removably received in said standard socket, and a regulating member oscillatably mounted thereon, said first named member being provided with a projecting arm; and anchoring means rigid with said housing and standard socket, 25 engaging said arm to prevent the unintentional disengagement of said first named regulating socket member from said standard socket.

2. In an electric lamp, the combination of 40 a housing; a standard socket rigidly mounted in said housing; a regulatable socket having a member removably received in said standard socket, and a regulating member oscillatably mounted thereon, said first named member being provided with a pair 45 of projecting arms; and anchoring means comprising inwardly projecting members carried by said housing, engaging portions of said arms for preventing the unintentional disengagement of said first named regulating socket member from said standard 50 socket.

In testimony whereof I affix my signature.

WILLIAM A. HARVEY.
